UNITED STATES PATENT OFFICE.

BERTRAND GEORGE MARTIN, OF LONDON, ENGLAND.

LOOSE-LEAF BOOK.

1,400,891.

Specification of Letters Patent. Patented Dec. 20, 1921.

Application filed April 30, 1921. Serial No. 465,662.

To all whom it may concern:

Be it known that I, BERTRAND GEORGE MARTIN, a subject of the King of Great Britain, residing at 12/13 Bow Lane, in the county of London, England, have invented certain new and useful Improvements in Loose-Leaf Books, (for which I have filed an application in Great Britain, No. 10,752, dated April 17, 1920,) of which the following is a specification.

This invention relates to loose-leaf books of the thonged type, that is, of the kind in which thongs, tapes or the like are secured in the front and back covers of the books, and the leaves which constitute the body of the book are slotted in such manner as to be capable of lateral movement on such thongs.

According to this invention the thongs entering one or both covers are secured to a thong attachment of metal, vulcanized fiber, or other suitable relatively stiff material, on which one cover is movable in such manner that the said cover can be slid toward or away from the center of the book telescopically in relation to the flexible portion of the book back which unites the two boards or relatively stiff portions of the back and front covers, and incloses the inner or slotted edges of the loose leaves. The cover slides freely on the thongs, the thong attachment being provided with a projecting tab to hold the thongs during such movement, that is, to prevent the thongs from following the covers when drawn closer together, this tab being adapted to act also as a fastening device for the movable cover when the book is closed.

In order that the said invention may be clearly understood and readily carried into effect, the same will now be described more fully with reference to the accompanying drawings, in which:—

Figure 1 represents the cardboard or other foundation of the front cover of a loose-leaf book, in a flat condition, and Fig. 2 represents the same partly folded.

Fig. 3 shows the cardboard or other foundation of the back cover of the book in a flat condition, and Fig. 4 the same partly folded.

Fig. 5 represents the thong attachment, thongs and tab assembled.

Fig. 6 shows a strip of metal from which the thong attachment can be made, and Fig. 7 illustrates the method of folding same so as to grip the thongs.

Fig. 8 shows an alternative method of fas-

tening the thongs and tab to the thong attachment.

Fig. 9 shows a book in which the boards shown in Figs. 1 to 4 and the thong attachment, Fig. 5, are assembled in a book having a pliable back, the thongs being tightened.

Fig. 10 shows the same book with the back fully expanded.

Fig. 11 shows a modified form of book to which this invention can be applied.

Fig. 12 is an external view of a modified form of the front cover of the book.

Fig. 13 is a fragmentary view taken through the longitudinal center of the tab E in Fig. 9.

Fig. 14 is a view of the parts shown in Fig. 13 in another position.

In the drawings, A indicates the front cardboard foundation, technically known as a sideboard, which is folded along the lines a' , a'' and has three holes a^3 , a^4 and a^5 in its central leaf. The sideboard B of the back cover, which is folded along the lines b' , b'' has the greater part of its central leaf cut away as shown in Fig. 3, and is provided with three holes b^3 , b^4 , and b^5 to house the thongs, and with smaller holes b^6 and b^7 for the reception of a catch such as that shown in Figs. 13 and 14. The thong attachment C to which the thongs D, d' , d'' , and tab E are attached, may either be composed of three laminations as shown in Figs. 6 and 7, secured by riveting through the thongs and tab, or may be as in Fig. 8 a stronger piece of metal or other material with longitudinal apertures c' , c'' , c''' , through which the thongs and tab are passed, turned back on themselves, and secured by stitching, riveting or adhesive means. The thongs being sunk in the holes a^3 , b^3 , etc., are guided thereby, and also are thus prevented from forming bulges or ridges in or on the bookbacks.

The end leaves or fly-leaves F of the book are made with narrow holes adapted to ride on the thongs.

The thongs being secured to the sideboard A in any suitable manner, the thong attachment is placed inside the sideboard B with the tab E projecting therethrough as shown in Fig. 9, and a pliable back G connected to the outer surface of the two sideboards. The loose leaves H of the book are slotted in known manner to embrace the thongs. The unused projecting portion of the tab E can be tucked into the front cover of the book when the book is closed, either passing

through a loop provided for that purpose on the finished book as shown at P in Fig. 12, or passing into the front sideboard through the rounded end of the hole α^4 , the length of the central thong d' being reduced to make room for the insertion of the tab. When some of the leaves have been taken out of the book, reducing its thickness, the tab is held and the cover pulled or pushed toward the center 10 of the back so as to tighten the covers upon the remaining leaves. Conversely when new leaves are to be added to the book, the cover may be pulled outward as in Fig. 10, exposing portions of the thongs on which the new 15 leaves can be threaded, after which the cover can be tightened up in the same way as aforesaid.

Any suitable catch may be provided to hold the tab E and sideboard B in any desired position relatively to each other. A well-known form of catch is shown by way of example in Figs. 13 and 14, comprising a fixed base J (Fig. 9) outside the sideboard, and a tongue j' appearing on the inner surface of the sideboard, this tongue being pivoted at j^2 and having a serrated flange j^3 adapted to grip the tab E when the tongue is laid against the sideboard as shown in Fig. 13, and to release the said tab when the 30 tongue is turned at right angles to the sideboard as shown in Fig. 14.

The usual binding or covering of cloth, leather, or the like can be secured to the book in known manner, the turned in edge 35 of such binding adjacent to the tongue j' being cut off just short of the said tongue.

In loose-leaf books in which a sliding pocket is arranged to inclose the back cover of the book, and to take up the slackness in 40 the cover caused by tightening the thongs, the tab may project through a slit cut in the outer edge of the said pocket, as shown in Fig. 11, wherein K indicates the pocket, k' , the location of the slit, and M an extension 45 of the pliable back secured to the thong attachment in the sideboard B.

The invention is equally applicable to books in which the pliable back G is omitted, the rear edges of the loose leaves H being 50 exposed between the end leaves F and the sideboards A and B. It is also applicable to books in which the thongs D traverse the end leaves F, which can be fitted with an outer cover or binding or such binding can loosely fit over same in known manner.

The locking device may be concealed within a flap or pocket on the cover, and operated from the inside or outside of such flap or pocket, or of the cover as desired.

60 The thongs should be secured at or pass

through the extreme inner edges of the front and back covers (which may be suitably strengthened) in order that the edges and not the faces of such covers should be drawn together.

The arrangement of three thongs D, d' , d^2 is considered a suitable one, but either the central thong or the two outer thongs may be omitted, or more than three thongs may be used.

What I claim and desire to secure by Letters Patent of the United States is:—

1. In a loose-leaf book, the combination of a cover, a thong attachment of stiff material, a flexible thong secured to said cover and to 75 said thong attachment, a second cover inclosing said attachment and slidably thereon, a tab secured to said attachment and projecting beyond said cover at the edge thereof remote from said thong, and means for connecting said tab to said first-named cover when the book is closed.

2. In a loose-leaf book, the combination of a cover, a thong attachment of stiff material, a plurality of parallel flexible thongs all secured to said cover and to said thong attachment, a second cover inclosing said attachment and slidably thereon, a tab secured to 85 said attachment and projecting beyond said cover at the edge thereof remote from said thongs, and means for connecting said tab to said first-named cover when the book is closed.

3. In a loose-leaf book, a thong attachment of stiff material, the combination of a 95 cover, a flexible thong secured to said cover and to said thong attachment, a second cover connected to the first-named cover by a flexible back, said second cover inclosing said attachment and slidably thereon, a tab secured to 100 said attachment and projecting beyond said second cover at the edge thereof and remote from said thong, and means for connecting said tab to said first-named cover when the book is closed.

4. In a loose-leaf book, the combination of a cover, a thong attachment of stiff material, a flexible thong secured to said cover and to 110 said thong attachment, a second cover inclosing said attachment and slidably thereon, a tab secured to said attachment and projecting beyond said second cover at the edge thereof remote from said thong, a catch on 115 said second cover adapted to engage said tab to limit the relative movement of said second cover and tab, and means for connecting said tab to said first-named cover when the book is closed.

BERTRAND GEORGE MARTIN.
